UNITED STATES PATENT OFFICE.

LOUIS A. CASGRAIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BREASTING MACHINE.

Application filed June 13, 1919, Serial No. 303,883. Renewed October 4, 1922. Serial No. 592,397.

To all whom it may concern:

Be it known that I, LOUIS A. CASGRAIN, a citizen of the United States, residing at Beverly, in the county of Essex and State of Massachusetts, have invented certain Improvements in Heel-Breasting Machines, of which the following description, in connection with the accompanying drawings, is a specification, like reference characters on 10 the drawings indicating like parts in the several figures.

This invention relates to machines for operating upon the breast portions of shoe heels and particularly to machines for forming the breast portions of Louis heels after 15 they are attached to their shoes.

Some heels, for example Louis heels, have their breast faces curved longitudinally of the shoe and are usually breasted by moving 20 relatively the heels and a rotary cutter transversely of the heel. It is frequently desired that the portions of the breast faces of such heels which extend heightwise of the heel be additionally curved convexly.

25 An object of this invention is to provide an improved machine organized to form a convex face on the heel extending heightwise of the heel by relative movement of the knife and heel transversely of the heel. Accordingly, a feature of the invention consists in an organization including shoe holding means and breasting means movable laterally of the heel in such manner as to 30 form on the heel a convex face extending heightwise of the heel. Preferably two knives are provided which act from opposite sides of the heel in curved paths to form on the heightwise extending portion of the heel breast a surface which is curved transversely 35 of the breast. As shown the knives are moved about an axis located at the rear of the breast to form two convex surfaces extending from the sides of the heel toward the center of its breast and coinciding to 40 form a surface convex toward the toe of the shoe.

45 Due to the springing of the knife operating mechanism and to the difficulty of maintaining the cutting edges of the knives in accurate parallelism it is impracticable to cause the knives to meet or even substantially to meet at the center of the breast, such a construction resulting either in actual contact of the knives and consequent dulling of

their edges, or, if the knives are set to prevent contact under any conditions of work, in the formation of an unsevered fin at the center of the heel which, when the chip is torn off, produces a blemish at the center of the heel.

50 Accordingly a feature of the invention consists in means for causing the knives, upon their initial movement in the cycle, to approach the center of the breast and then for causing one knife to retract while the cutting movement of the other continues to sever the chip completely from the heel. This results in the formation of a smooth 55 breast face by the initial action of the cutters and removes any line of demarcation 60 between the surface formed by one knife and that formed by the other knife.

65 The base portion of a Louis heel extends substantially lengthwise of the heel forwardly of the shoe along the shank and 70 should be convex in form with its forward edge flush with the surface of the shoe shank.

75 A further feature of the invention consists in a knife shaped to form both the heightwise and lengthwise extending portions of the breast by relative transverse movement of the shoe and knife and means for relatively moving the shoe and knife, during the 80 relative transverse movement of the shoe and knife, in the direction of the height of the heel to cause the portion of the knife which forms the base or lengthwise extending portion of the heel to follow the convex curve 85 of the shank and to trim the forward edge of that portion flush with the surface of the shank. As shown the two knives are employed which are moved bodily during 90 their approaching movement and in such time relation thereto as to form the base 95 portion of the heel as described.

95 Since the knives have a predetermined path of movement it is essential that the shoe be accurately positioned relatively to the path of the knives. To this end a 100 further feature of the invention consists in stop members mounted upon arms movable laterally of the shoe in a plane extending generally lengthwise of the shoe to carry the stops into and out of position over the 105 shoe shank, the shoe being located against the stops during operation of the knives. As shown these stop members, when over

the shoe bottom, are located beneath rigid abutments on the machine frame which prevent any vertical movement of the members by pressure of the shoe against them when 5 the shoe is raised and positively locate the shoe vertically relatively to the knives. As shown the stop members are movable laterally out of the way of the shoe to allow free movement of the shoe longitudinally into 10 and out of operative relation to the knives.

After the breasting operation and while the shoe is still held in the machine it is desirable to perform the operation of scalloping the heel. This operation consists in 15 forming a concavity in the portion of the heel breast adjacent to the top lift and is best performed by means of a rotary cutter.

Another feature of the invention consists in a rotary cutter which is arranged to move 20 heightwise of and toward the heel to treat the heel breast. Preferably the cutter is located normally at one side of the shoe and out of the way of the shoe as it is inserted into and removed from the machine 25 and means is provided for moving the cutter laterally and rearwardly of the shoe to locate it above the heel prior to its movement heightwise of the heel to treat the heel breast. As shown, the cutter is frusto-conical 30 in shape with its smaller end toward the heel. The cut formed by the cutter has therefore a larger radius of curvature at the portion adjacent to the tread face of the heel and a smaller radius where it merges 35 into the convex portion of the breast face.

These and other features of the invention, including various novel combinations and organizations of parts, will appear more fully from the following detailed description 40 when read in connection with the accompanying drawings and will be pointed out in the appended claims.

In the drawings,—

Fig. 1 is a side elevation of the machine, 45 part of the frame being broken away to show the mechanism in the base portion;

Fig. 2 is a front elevation, part of the frame being broken away to show the mechanism located therein;

Fig. 3 is a plan view partly in section of the machine;

Fig. 4 is a vertical section of the head of the machine on the line 4—4 of Figs. 2 and 3;

Fig. 5 is a transverse section on the line 55 5—5 of Fig. 1.

In the drawings, the numeral 2 indicates the frame of the machine in the lower part of which is mounted a shaft 4 having thereon various cams, to be referred to herein-after, by which certain parts of the operating mechanism with which the machine is provided are operated. Loosely mounted on one end of the shaft 2 is a driving pulley 6 to be driven continuously by belt connec-

tion to a source of power. A suitable clutch is provided between the shaft 4 and pulley 6 to cause the shaft to be driven through a single revolution at each depression of a treadle 8.

The work support comprises a post 10 on the upper end of which is adjustably mounted a last pin 14. The post 10 is arranged for longitudinal movement in a jack sleeve member 20 which is pivotally supported at 70 21 on the outer end of a lever 22 fulcrumed to the frame at 24. The member 20 is provided with projections 26, 28 which limit swinging movement of the member on its pivot 21 inwardly and outwardly, respectively, by engaging the lever 22. The post 10, normally, is yieldingly sustained by a light spring. Before the machine is started the post 10 is free to be depressed against the spring and to be swung in and out about the pivot 21. When in outwardly swung position a shoe is placed upon the pin 14 and swung toward the machine, being at the same time depressed to enable the heel to be positioned beneath a tread plate 34. Rearward movement of the shoe is limited by a back stop 36 on the plate 34 which engages the rear face of the heel. The longitudinal tilt of the shoe is determined by a rest 38 adjustably secured at 40 to a projection 42 on the frame 2 and arranged to engage the bottom of the forepart of the shoe. A similar work support is shown and more fully described in my application Serial No. 290,670, filed April 17, 1919.

It is important, as will later appear, that the shank of the shoe be located in a pre-determined position vertically, and it is also important that there be no obstruction in the way of the shoe during its movement into the machine as described. Accordingly two shank stops 50, 52 are provided which move laterally of the shoe over the shank portion thereof before the jack is raised, the movement being preferably effected by a connection with the treadle 8 so that a preliminary movement of the treadle will position the stops over the shoe, and further movement of the treadle will start the machine. The stops 50, 52 are on the ends of horizontal arms 54, 56 which are loosely fulcrumed respectively on vertical shafts 58, 60. The arms 54, 56 have extensions 62, 64 (Fig. 3) at the rear of their pivots 58, 60 which extensions are adapted to be engaged by a wedge member 66 arranged to slide horizontally in ways formed in a part 67 secured at 69 to a stud 71 extending rearwardly from the frame. Movement of the wedge member 66 separates the extensions 62, 64 and causes the shank stops 50, 52 to approach each other and assume positions over the shoe bottom. The wedge member 66 is moved by a suitable connection to an arm 68 (Fig. 4) upon a rock shaft 70 which has an arm 72 connected to a 100 105 110 115 120 125 130

rod 74 the lower end of which rests upon the rear end of the treadle lever 8. The rod 74 is pulled downwardly by a spring 75 (Fig. 1) connected to the rod and to a pin on the frame. It will be seen that depression of the lever preliminary to starting the machine will push upwardly on the rod 74 and cause the stops 50, 52 to be positioned over the shank of the shoe. The stop arms 54, 56 have surfaces 76, 78 (Fig. 5) which lie beneath projections 80, 82 (Fig. 2) from the frame 2 and prevent any upward springing of the arms when pressure is applied by the shoe to the stops 50, 52.

Immediately after the machine starts the post 10 is locked against depression by a pawl block 84 which is arranged to engage teeth formed in the rear face of the post 10 and is urged into locking engagement therewith by a leaf spring 85. The pawl block 84 is normally held out of engagement with the post 10. For this purpose the block 84 is mounted on the end of an arm 86 of a rock shaft fulcrumed on the sleeve member 20 and having an arm 88 connected by a link 90 to a lever 92 fulcrumed at 94 on the lever 22 and held from movement by a link 96 which connects the lever 92 to the frame 2. The lever 22 extends into the machine frame and at its rear end has a link 97 which connects it to a horizontal arm 98 (Fig. 2) from a rock shaft 100 which is mounted in the frame and has a depending arm 102 carrying a roll arranged to engage an edge cam 104 on the shaft 4. In the drawings the machine is represented as having been started, the shaft 4 having moved through about 30 degrees. This has caused the arm 102 to be moved to the left by its cam 104, effecting a downward pull on the link 97 and causing the outer end of the lever 22 to move upwardly. During this movement the arm 86 which operates the pawl 84 has been held from movement by the connections described and has caused the pawl block 84 to engage the teeth on the post 10. A slight upward movement of the jack member 20 before the post 10 is locked is permitted by a lost motion connection between the link 90 and the lever 92. In conjunction with the upward movement of the shoe and the shoe support, by reason of its connection with the outer end of the lever 22, there is a downward movement of the tread plate 34 which is effected as follows: The tread plate 34 (Fig. 4) is mounted on the front end of a lever 106 fulcrumed at 108 at the rear of the machine and having connected thereto between its ends a rod 110 the lower end of which is connected to the rear arm of the lever 22 at 112 (Fig. 1). Downward movement of the lever 106 is effected yieldingly through a spring 114 (Fig. 4) arranged between the lever 106 and a nut 116 on the end of the rod 110. The lever 106 is lifted by a collar 115 on the rod 110. When the machine starts, the jack will be raised a predetermined amount determined by the cam 104 to force the shoe against the shank stops and this movement will force the shoe with equal pressure against the shank stops 50, 52 since the variation in the heights of lasts is taken care of by the relative movement of the post 10 and sleeve 20 before the locking pawl 84 operates to prevent such relative movement.

The machine is provided with two breasting knives 120 and 122 which operate from the sides of the heel toward the center of the heel and which, in order to form a convex contour on the portion of the breast face which extends heightwise of the heel, are arranged to move about the center of a shaft 124 located over the heel and rearwardly of the heel breast. Knife carriers 126, 128 project downwardly, one from the shaft 124 and the other from a sleeve 130 surrounding the shaft 124. The sleeve 130 has keyed thereto a segmental gear 134 meshing with a similar segmental gear 136 pinned to the shaft 60. The shaft 124 has fixed thereto a segmental gear 138 meshing with a segmental gear 140 secured to the shaft 58. Obviously rocking movement of the shafts 58, 60 in opposite directions will cause the knives to approach each other and to move in a curved path across the breast face of the heel. To effect operation of the shafts 58, 60 they are extended downwardly through suitable bearings and provided at their lower ends (Fig. 2) with arms 142, 144 carrying cam rolls which engage separate cam paths 143, 145 (Fig. 1) formed in a cam block 146 on the shaft 4.

Since the shank of a shoe is transversely convex, it is important to effect relative movement of the knives and shoe heightwise of the heel as the knives approach the center of the heel breast from the two sides in order to give the base portion of the heel 110 which extends substantially lengthwise of the shoe an upward convexity which corresponds at its forward edge to the curve of the shank and merges into the convexity extending heightwise of the heel and formed by movement of the knives about the axis of the shaft 124 and sleeve 130. In the construction shown the knives are arranged to be raised as they approach the center of the breast to cause their lower portions to follow the curve of the shank as they approach each other. To effect this the shaft 124 and sleeve 130 are mounted for turning movement in a slide 148 guided for vertical movement in the frame 2 by gibbs 149, 149, as will be clear from Fig. 3. The slide on its rear face is provided with teeth (Fig. 4) which engage a toothed segment on the forward end of a lever 150 fulcrumed at 152 to the frame and extending to the rear of the ma-

chine where it is connected by a rod 154 to a lever 156 (Figs. 1 and 2) fulcrumed at 158 to the machine frame and having between its ends a roll 160 which engages a 5 suitable cam path in the rear face of the cam block 146 which effects a downward pull on the rod 154 and causes the knives to be raised as they approach the center of the heel. The teeth on the segments 136, 140 10 are of sufficient vertical extent to permit the required vertical movement of the segments 134, 138 without disengagement of the segments.

It will be clear that the knives should not 15 meet in the center of the heel since it would be impracticable so to adjust the knives that they would approach closely enough to make a clean cut without sometimes coming in contact. Moreover, if the knives are ad- 20 justed so that there is a substantial space between them, although the chip might be torn off, it would produce a "fin" or rough place at the center of the heel which it would be difficult to remove in the buffing operation. 25 These difficulties are overcome in the present machine by a construction which causes the knives to approach each other and nearly to meet at the center of the heel but not to approach sufficiently close to cause the 30 chip to break off. Then, following this initial movement, the movement of one knife is arrested and its retraction begun while the movement of the other knife is continued sufficiently past the center completely 35 to sever the chip. This result is effected by suitably designing the cam paths 143, 145 in the edge of the cam block 146 to cause the movement of the knives to take place as described.

40 After the shoe has been breasted in the manner described, it is desirable to scallop the heel and in the construction shown automatic means for effecting this operation is provided. A frusto-conical cutter 162 is 45 arranged normally above the shoe and at one side of its longitudinal median plane so as to be out of the way of the shoe as it is swung into the machine. Means is provided for moving the cutter laterally and rear- 50 wardly of the shoe to a position over the breast portion of the toplift of the heel and causing it to descend into engagement with the heel to form the scallop. The cutter 162 is on a vertical shaft 164 (Figs. 3 and 55 4) having at its upper end a pulley 166 from which a belt 168 passes over idlers 170, 171 loose on a shaft 172 and around a pulley 173 on a counter shaft 174 (Fig. 1). On the opposite end of the counter shaft is 60 a pulley 175 connected by a belt 176 to a separate crowned surface on the constantly driven pulley 6. The shaft 164 has bearings in a vertically movable slide 180. The slide 180 is mounted in a segmental shaped mem- 65 ber 182 which in turn is mounted in curved

guides 184 formed in a part 185 fixed to the frame so that the member 182 may move about its center of curvature. An arm 186 fixed to the member 182 is connected by a link 188 to an arm 190 of a rock shaft 192 70 journaled in the frame and having an arm 194 connected by a link rod 196 to a lever 198 fulcrumed at 200 to the machine frame and carrying a cam roll 202 which is acted upon by a cam path 203 in the front face 75 of the cam block 146 which causes, through the connections described, the arm 190 to be moved to the left (Fig. 2). This effects movement of the segmental member 182 about its center of curvature (Fig. 3) to 80 carry the cutter shaft from its initial position forwardly of and at one side of the heel into position over the toplift of the heel. The link 188 has universal joint connections at its ends to the arm 186 and to the arm 190 respectively. The slide 180 is next moved downwardly to cause the cutter 162 to operate upon the heel and this is effected by means of a lever 204 fulcrumed at 206 to the machine frame and having at 85 its forward end segmental teeth to engage corresponding teeth 205 on the slide 180. At its other end the lever 204 is connected by a rod 208 to a lever 210 fulcrumed at 212 to the machine frame and having between 90 its ends a cam roll 214 which engages a cam path in the rear face of the cam block 146 suitably designed to effect, at the proper time in the cycle of the machine, a downward movement of the slide 180 to cause the cutter 162 to effect the scalloping operation. The teeth 205 on the slide 180 are extended 95 concentrically with the curve of the segmental member 182 to permit turning of the segmental member and the slide without disengaging the teeth 205 from the end of the lever 204.

Having thus described my invention, what I claim as new and desire to secure by Letters Patent of the United States is:

1. In a machine of the class described, the combination of cutting means constructed and arranged to traverse the heel breast in a curved path to form a convexly curved surface on the heightwise extending portion of the heel breast, and means for holding a shoe and its attached heel in predetermined relation to the path of the cutting means.

2. In a machine of the class described, the combination of a knife constructed and arranged to traverse the heel from side to side in a curved path conforming to the desired curve to be formed on a portion of the heel breast which extends heightwise of the heel, and means for holding the heel and the shoe to which it is attached in predetermined relation to the path of the knife.

3. In a machine of the class described, the combination of a shoe support, a plurality of

- Knives arranged to move from the sides of a heel toward its center in paths which are convex toward the toe of the shoe, and means for effecting additional movement of the 5 knives to effect complete severance of the breast chip from the heel.
4. In a machine of the class described, the combination of a shoe support, and a plurality of knives arranged to have an oscillating movement about a common axis located rearwardly of the heel breast in effecting their action upon the heel breast. 10
5. In a machine of the class described, the combination of a shoe support, and a plurality of knives arranged to move from the sides of the heel toward its center in a circular arc the center of which is located rearwardly of the heel breast. 15
6. In a machine of the class described, the 20 combination of a shoe support, a plurality of knives arranged to move from the sides of the heel toward the center in a path which is convex toward the toe of the shoe, means to cause one knife to stop before reaching the center and to retract, and means for causing the other knife to move past the center to sever the chip before retraction.
7. In a machine of the class described, the 25 combination of a shoe support, a plurality of knives arranged to move from the sides of the heel toward the center, and means for effecting bodily relative movement of the shoe and knives in the direction of the height of the heel during their approaching movement to cause the portions of the knives next to the shank to follow the curve of the shank. 30
8. In a machine of the class described, the 35 combination of means for holding a heel, a plurality of knives mounted for movement about an axis extending heightwise of the heel, means for moving the knives relatively to form a curved face on the heel and partially to sever the chip, and means for further operating the knives completely to sever the chip. 40
9. In a machine of the class described, the 45 combination of means for holding a heel, a plurality of cutters, means for relatively moving the work and one cutter to initiate the cutting operation from one side of the work and form a convex face on the heel extending heightwise thereof, and means for relatively moving the work and the other cutter to complete the cutting operation along the same curve. 50
10. In a machine of the class described, the 55 combination of a shoe support, a plurality of knives constructed and arranged to form on the heel breast a convex face extending heightwise of the heel, and means for relatively operating the shoe support and knives to effect the breasting operation. 60
11. In a machine of the class described, 65 the combination of a shoe support, and a plurality of knives arranged to approach each other from opposite sides of the heel, said knives being constructed and arranged to form a convex face on the heel breast extending heightwise of the heel. 70
12. In a machine of the class described, the combination of a shoe support, and a plurality of knives arranged to oscillate about a center located rearwardly of the heel breast 75 and to act simultaneously upon the heel breast during their oscillating movement.
13. In a machine of the class described, the combination of a shoe support, and a plurality of knives arranged to oscillate during 80 their cutting action upon a heel about a common axis located rearwardly of the heel breast and substantially parallel to the breast.
14. In a machine of the class described, the combination of a shoe support, and a plurality of knives arranged to move about an axis perpendicular to the plane of the tread face of the shoe from the sides of the heel toward its center in circular arcs to form a 85 convex face on the heel breast. 90
15. In a machine of the class described, the combination of a shoe support, a plurality of knives arranged to move from the sides of the heel toward the center about an axis extending heightwise of the heel, and means to cause one knife to stop before reaching the center and to retract and the other knife to move past the center to sever the chip before retraction. 95
16. In a machine of the class described, the combination of a shoe support, a plurality of knives mounted to move from the sides of the heel toward the center, and means for relatively moving the shoe and knives in the direction of the height of the heel during their approaching movement to cause the portions of the knives next to the shank to follow the curve of the shank. 100
17. In a machine of the class described, the combination of means for holding the work, a plurality of knives constructed and arranged for movement about an axis substantially parallel with the face of the work to be treated by the knives, and means for moving the knives in the initial operation of the knives upon the heel first in opposite directions partially to sever the chip from the face of the work and then in the same direction completely to sever the chip. 110
18. In a machine of the class described, the combination of means for holding a shoe, a plurality of knives, means for effecting relative movement of the knives to form a curved face on the shoe heel extending heightwise of the heel and partially to sever the chip from the heel, and means for moving both knives and the heel relatively to complete the severance of the chip. 120
19. In a machine of the class described, the combination of means for holding a heel, 125

a plurality of knives, means for moving the knives in opposite directions to form a convex face on the heel extending heightwise of the heel and partially to sever the chip from the heel, and means for moving one knife farther than the other knife is moved completely to sever the chip.

20. In a machine of the class described, the combination of means for holding the work, a plurality of knives having portions of their cutting edges of different extents and in different planes, and means for moving the knives about an axis parallel to the major portion of their cutting edges first in opposite directions and then in the same direction to sever the chip from the work.

21. A heel breasting machine comprising a knife of suitable contour movable in a direction from side to side of the breast of a heel, and a rotary cutter movable in the direction of the height of the heel to treat a portion of the heel breast.

22. A heel breasting machine comprising a knife of suitable contour movable in a direction from side to side of the breast of the heel, a rotary cutter movable in the direction of the height of the heel to treat a portion of the heel breast, and automatic means for operating the knife and cutter successively in timed relation.

23. A heel breasting machine comprising a plurality of knives movable simultaneously from opposite sides of the heel about an axis located rearwardly of the heel breast toward the center of the breast, a rotary cutter, and means for first operating the knives to breast the heel and then operating the rotary cutter to form on the portion of the breast adjacent to the toplift a concavity merging into the cut made by the knives to form a breast face having portions of reverse curvature.

24. In a machine of the class described, the combination of a plurality of breasting knives movable transversely of the heel breast toward its center, a shoe support means for operating the knives to breast the heel, and means for relatively moving the knives and shoe support during movement of the knives to cause the knives to follow the transverse curve of the shank.

25. A heel breasting machine comprising means for holding a shoe in fixed position, a rotary cutter having its axis extending in the direction of the height of the heel, and automatic means for moving the cutter in the direction of its axis to treat the heel breast.

26. A heel breasting machine comprising shoe and heel holding means, a rotary cutter having its axis extending in the direction of the height of the heel and located at one side of the shoe, automatic means for moving the cutter to position its axis over the shoe, and means for moving the cutter in the

direction of its axis to cause it to treat the heel breast.

27. A heel breasting machine comprising a plurality of knives movable simultaneously from opposite sides of the heel toward the center of the heel breast, a rotary cutter arranged at one side of the shoe, and means for first operating the knives to breast the heel and then moving the rotary cutter over the shoe and heightwise of the heel to form on the portion of the breast adjacent to the toplift a concavity merging into the cut made by the knives.

28. In a machine of the class described, the combination of a breasting knife movable transversely of the heel breast and formed to treat the breast of the heel and the forwardly extending base portion of the heel, a shoe support, means for operating the knife to breast the heel, and means for relatively moving the knife and shoe support during movement of the knife to cause the knife to follow the transverse curve of the shank and to form the base portion of the heel with a convex surface.

29. A heel breasting machine comprising a knife of suitable contour movable in a direction from side to side of the breast of a heel, a rotary cutter, means for moving the cutter over the heel, and means for moving the cutter in the direction of the height of the heel to treat the heel breast.

30. A heel breasting machine comprising a plurality of knives of suitable contour movable in directions from the sides of the breast of the heel toward its center, a rotary cutter movable in the direction of the height of the heel to treat a portion of the heel breast, and automatic means for operating the knives and cutter successively in timed relation.

31. A heel breasting machine comprising a plurality of knives movable about an axis extending heightwise of the heel, means for moving the knives simultaneously from opposite sides of the heel toward the center of the heel breast and then moving the knives in the same direction and retracting them, a rotary cutter, and means for then operating the rotary cutter to form on the portion of the breast adjacent to the toplift a concavity merging into the cut made by the knives.

32. In a machine of the class described, the combination of a breasting knife movable transversely of the heel breast, a shoe support for holding the shoe in fixed position, means for operating the knife to breast the heel, and means independent of the shoe for moving the knife relatively to the shoe support during the transverse movement of the knife to cause the knife to follow the transverse curve of the shank.

33. In a machine for breasting heels, the combination of arms movable in a plane ex-

- tending generally lengthwise of the shoe, stops on said arms and movable by the arms from a position laterally beyond the shoe to a position over the shoe shank, means 5 for relatively moving the shoe and said stops to hold the shoe, and means for breasting the heel while so held.
34. In a machine for breasting heels, the combination of stops movable in a plane 10 substantially parallel with the shoe shank from a position laterally beyond the shoe to a position over the shoe shank, means for relatively moving the shoe and said stops to hold the shoe, means above the stops into 15 operative relation to which the stops are carried by their movement over the shoe to take the thrust of the shoe and stops when the stops are in operative position, and means for breasting the heel while so held.
35. In a machine for breasting heels, the combination of arms movable in a plane substantially parallel with the shoe shank, stops on said arms movable therewith from a position laterally beyond the shoe to a 20 predetermined position over the shoe shank, means for jacking the shoe against the stops, and breasting means acting to form the base of the heel to correspond to the transverse curve of the shank.
36. A heel breasting machine comprising a knife of suitable contour movable in a direction from side to side of the breast of a heel, a rotary cutter, and means for moving the cutter heightwise of the heel to treat the heel breast.
37. In a heel breasting machine, the combination of cutting means movable in a direction from side to side of the breast of a heel, a rotary cutter movable heightwise of the heel to treat the heel breast, and means 40 for operating the cutting means and the rotary cutter successively in timed relation.
38. In a machine of the class described, the combination of shoe positioning means and a rotary cutter mounted to swing from a position laterally of the shoe into position above the heel and for sliding movement heightwise of the heel to treat the heel breast. 45
39. In a machine of the class described, the combination of shoe positioning means, a rotary cutter mounted to swing from a position laterally of the shoe into position above the heel and for sliding movement heightwise of the heel to treat the heel breast, and means acting automatically to effect said movements of the cutter. 50
40. In a machine of the class described, the combination of shoe positioning means, a rotary cutter having its axis parallel to the direction of the height of the heel and normally located forwardly of and at one side of the heel, and means for moving the cutter lengthwise of and transversely of the heel to a position above the heel and then 60 toward the heel to treat the heel breast. 65
41. In a machine of the class described, heel holding means, a rotary cutter, means for moving the cutter over the heel, and means for moving the cutter heightwise of the heel to treat the heel breast. 70
42. In a machine of the class described, heel holding means, a rotary cutter, and automatic means for relatively moving the holding means and the cutter transversely of the heel and lengthwise of the heel. 75
43. In a machine of the class described, shoe positioning means, a breasting knife, and means for moving the knife heightwise of and transversely of the heel in its cutting operation. 80

In testimony whereof I have signed my name to this specification.

LOUIS A. CASGRAIN.
